UNITED STATES PATENT OFFICE.

AUGUST KAPPENBERG, OF NEW YORK, N. Y.

SMOKER'S STAND.

Application filed July 21, 1926. Serial No. 124,010.

This invention relates to smokers' articles and aims as its principal object to provide means preferably associated with an ash tray for supporting a package of cigarettes, 5 cigars, matches, or other analogous packed articles so as to dispose the same in tiers and in different planes whereby to facilitate their removal.

The invention furthermore resides in the 10 provision of a packaged article supporting means which is extremely simple in its construction, economical to produce, and efficient in its purpose.

With the above recited and other objects 15 in view, reference is had to the following specification and accompanying drawings in which there is exhibited one example or embodiment of the invention which is in no way intended as a limitation upon the scope 20 of the appended claims as it is to be clearly understood that variations and modifications which properly fall within the scope of said claims may be resorted to when found expedient.

25 In the drawings—

Figure 1 is a perspective view of an ash tray equipped with a supporting means constructed in accordance with the invention;

Fig. 2 is a plan view thereof;

30 Fig. 3 is a fragmentary transverse sectional view taken approximately on the line 3—3 of Fig. 2.

Referring to the drawings by characters of reference, 10 designates an ash tray, to 35 one edge of which an upstanding substantially U-shaped clip 11 is secured, including parallel side leaves 12 and 13 joined at the lower end by a bight 14. Secured to the upper surface of the bight in any desired manner, is an element 15, such as a block, the upper end of which is stepped to provide horizontal supporting surfaces 16, 17 and 18 disposed in relatively different planes. The side faces of the element or block 15 are 40 spaced from the clip leaves 12 and 13 and the major cross-sectional area of the block is approximately equal to the internal measurement or area of the package P which is to be supported thereby so that when the 45 upper and lower ends of the packages are torn away or removed the same may be inserted over the block in the manner illustrated in Fig. 3, with the sides of the package interposed and maintained between the 50 side faces of the block and the inner surfaces of the leads 12 and 13. In this manner,

the horizontal stepped surfaces 16, 17 and 18 engaging the lower ends of the cigarettes C or other contents of the package, effect disposition of the upper ends thereof in 60 tiers and in different planes so that the withdrawal or removal of the cigarettes or other articles from the package is greatly facilitated. If desired, the leaf 13 may be provided with a match-book-supporting 65 means consisting of tongues or similar elements 19 cut and bent from the leaf.

It is obvious, within the scope of the invention, that the device while particularly designed for cigarettes, may be employed 70 for use in connection with packaged cigars, matches, or any other articles.

What is claimed is:

1. A smoker's article, including a substantially U-shaped resilient clip for supporting 75 a package of elongated articles, and means in the bight of said clip engaging through the lower end of the package and with the lower end of the packaged articles for disposing the upper ends thereof in tiers and 80 in different planes to facilitate their removal from the package, said means consisting of a block disposed within the clip and having its side faces spaced from the leaves of the clip and formed with stepped upper 85 ends defining supporting surfaces arranged in different planes.

2. A smoker's article, comprising a member formed with stepped portions arranged in different planes and adapted for insertion through the lower end of a cigarette 90 package for engaging the lower ends of the cigarettes to dispose the upper ends thereof in tiers and in different planes to facilitate their removal from the package. 95

3. A smoker's stand including a clip for supporting packaged elongated articles, and means in said clip engaging the lower ends of the articles for disposing the upper ends of said articles in tiers and in different 100 planes to facilitate their removal from the package.

4. A smoker's stand, including a clip for supporting packaged elongated articles, and means in said clip for engaging through the 105 lower end of the package and with the lower ends of the articles for disposing the upper ends of the articles in tiers and in different planes to facilitate their withdrawal from the package.

AUGUST KAPPENBERG.
